UNITED STATES PATENT OFFICE.

JOHN C. THOMSON, OF ROCK ISLAND, ILLINOIS.

MAILING-MACHINE.

No. 867,447.

Specification of Letters Patent.

Patented Oct. 1, 1907.

Application filed December 15, 1906. Serial No. 347,979.

To all whom it may concern:

Be it known that I, JOHN C. THOMSON, residing at Rock Island, in the county of Rock Island and State of Illinois, have invented certain new and useful 5 Improvements in Mailing-Machines, of which the following is a specification.

My invention relates to certain new and useful improvements in mailing machines and it particularly relates to that type of mailing machines in which 10 means are provided for pasting labels on magazines, papers or other articles, the labels being pasted on the article by the machine and cut from a continuous strip.

Primarily, my invention has for its object to provide a machine of this character of a very simple and effective 15 construction, which can be easily and cheaply manufactured, which will be rapid and accurate in its operation, and which will readily and effectively serve its intended purposes.

In its generic nature, my invention comprises a support upon which a reel is mounted on which the labels are held, the labels being printed on a continuous strip, means mounted on the support for feeding the strip toward the paper upon which the label is to be pasted, means for gumming the label, and means for cutting 25 the label from the strip and simultaneously applying it to the article to be labeled.

In its more detailed nature, my invention comprises certain novel construction, combination and arrangement of parts all of which will be first described in 30 detail and then be specifically pointed out in the appended claims, reference being had to the accompanying drawings, in which:

Figure 1, is a perspective view of my invention applied for use. Fig. 2, is a top plan view thereof. 35 Fig. 3, is a side elevation of my invention. Fig. 4, is a vertical, longitudinal section on the line 4—4 of Fig. 2. Fig. 5, is a detail perspective view of the pivotally mounted roller carrying frame. Fig. 6, is a detail perspective view of the cutting knife and presser. Fig. 7, 40 is a detail perspective view of the adjustable guide and the shaft upon which it is mounted. Fig. 8, is a detail side elevation of a portion of my invention. Fig. 9, is a view of a slightly modified form of my invention showing how the same may be operated by 45 mechanical power instead of a foot lever as in the form shown in Figs. 1 to 3 of the drawings. Fig. 10, is an enlarged section on the line 10—10 of Fig. 2. Fig. 11, is an enlarged detail perspective view partly in section, showing the presser knife adjusting means. Fig. 12, 50 is a partial perspective view of the paste-pan, showing scraping front.

Referring now to the accompanying drawings, in which like letters and numerals of reference indicate like parts in all of the figures it will be seen that 1

represents the table or stand upon which the bed plate 55 2 of the machine may be secured in any approved manner. The bed plate of the machine comprises an elongated portion 2^a and a laterally projecting portion 2^b, as clearly shown in Fig. 2 of the drawings. The front edge of the elongated portion 2^a of the bed plate 60 2 is arranged to project over the front edge 1^a of the table 1 while the rear end of the elongated portion 2^a of the bed plate 2 is provided with a pair of bearing posts 3—3, connected by a transverse shaft 4 upon which the reel or bobbin 5 is mounted.

The bobbin 5 is secured to turn with the shaft 4 by a key or otherwise, as indicated in dotted lines on Fig. 2, a crank 4^a being provided on the shaft 4 for the purpose of winding the endless tape or sheet of address portions on the bobbin 5.

At the forward end of the bed 2, the same is provided with a pair of upwardly projecting portions 2^c—2^c at each side thereof and with a curved guide 2^d to permit the article to be pasted to pass under the bed plate for a purpose presently more fully understood.

Between the upwardly projecting portions 2^c of the bed plate and the reel or bobbin 5 and adjacent the forward portion of the bed plate, a paste-pan 6 is mounted on the bed plate 2 and parallel with the elongated portion 2^a thereof. The rear end of the paste-pan 6 is formed by a drum 6^a. The paste pan is formed with a pair of upwardly projecting posts 6^b having bearing portions in which a shaft 7 is fulcrumed. On the shaft 7, a baffle plate 8 is secured to turn therewith, the baffle 8 having a bottom bar 8^b, as shown. 85 The shaft 7 has a finger engaging turn portion 7^t, by means of which the shaft 7 may be turned.

Mounted on the shaft 7 is a pair of collars 9^a which are laterally adjustable on the shaft 7 and held in position by set screws 9^b, as most clearly shown in Fig. 90 2. Fixedly secured to or formed with the collars 9^a are guides 9 which project forwardly toward the front of the machine, and between which the elongated strip or label 100 is adapted to pass.

10 designates a roller having its shaft 10^a mounted in 95 bearing apertures 6^d in the side walls of the paste-pan 6. The paste-pan, it should be also stated, preferably has its front formed with a slanting end 6^e, as shown, and for a purpose presently understood.

11^a—11^b designate pairs of transversely grooved 100 rollers carried by a shaft 11 journaled in bearing apertures in the uprights 2^e—2^e and adjacent the bed plate 2^a, the shaft 11 projecting through one of said uprights 2^e and carrying a pinion 11^b for a purpose presently understood.

12 designates a supplemental frame hingedly or pivotally mounted at 12^a to the uprights 2^e of the bed plate 2. The supplemental frame 12 is in the nature of a

yoke member whose pivoted end 12^b carries a coil spring 13 which has one end secured to the portion 12^b and has its other end lying against the bed plate 2 so that the frame 12 is normally held parallel with the bed plate 2, a stop pin 12^a being provided on one of the arms of the supplemental frame 12 to engage the upright 2^a and limit the movement of the frame 12 under the influence of the spring 13.

14 designates a thumb operated member which is 10 pivotally mounted to the upright 2^a and is adapted to engage the pin 12^a at times to lift the frame 12 and move it on its pivot. The frame 12 at the front is formed with inwardly projecting portions 12^d on the ends of which an upper pair of rollers 15 are journaled, 15 which rollers 15 coöperate with one pair of rollers 11^a and are normally held in engagement with the rollers 11^a by the action of the coil spring 13. Mounted between the uprights 2^a at the extreme front end thereof, is a knife blade 16 which is secured to the bed plate 2 20 by screws 16^a, and the knife blade 16 coöperates with the knife blade 17 on a presser member 18 hereinafter again referred to. Journaled on a lug or stub shaft 2^c projecting from one of the uprights 2^a is a gear wheel 19 which meshes with a pinion 11^b hereinbefore referred to, and the gear wheel 19 is attached to a ratchet 20 that is also mounted on the stub shaft 2^c.

21 designates brackets fastened to the laterally extending portion 2^b of the bed plate 2 between which brackets the fulcrum or shaft portion 22^a of the arm 22 30 is pivotally mounted. The arm 22 projects laterally with the paste-pan 6 toward the front of the machine, and at the front the arm 22 has a projecting portion 22^b on which the presser and movable cutter member 18 is pivotally mounted, and secured in place by a 35 milled nut 22^c and a collar 22^d, as shown in the drawings.

The shaft portion 22^a in the arm 22 carries an upwardly projecting post 23 which is bifurcated as at 23^a and provided with alining apertures 23^b. Mounted 40 on a pin 24^a which passes through one set of apertures 23^b is a pawl 24 which has a hook end 24^d to engage the ratchet 20 to move the same in a manner presently understood. The arm 22 is slotted, as at 22^c to permit passage of a rod 25 which is fulcrumed in the arm 22 45 on a pin 25^a. The rod 25 connects with the operating arm 26 that is pivotally mounted at 26^a to bearing brackets 27 secured beneath the table 1. The arm 26 is normally held adjacent the table to raise the arm 22 by a coil spring 28. A coil spring 24^c is provided 50 for holding the pawl 24 in engagement with the ratchet 20, and by reason of the series of apertures 23^b in the post 23, the pivot or fulcrum of the pawl 24 can be varied as conditions may require. The arm 26 is formed with a lever 29 which has a foot engaging portion 29^a, by means of which the lever 29 can be operated to swing the arm 26 on its fulcrum 26^a against the tension of the spring 28.

30 designates a leaf spring which has its free end 30^a arranged to be engaged by the heel 18^a of the presser 60 18. The spring 30 has its other end adjustably secured to the portion 2^b of the bed plate by a set screw 31.

32 designates a receiving board upon which the articles to be addressed are received, and the receiving board is provided with a hinged wing 32^a adjustable 65 by a leg 2^x that is hingedly secured to the wing be-

neath the same. The object in providing the hinged wing 32^a is for conveniently feeding and handling the articles to be pasted.

The cutter 17, it should be stated, is adjustably secured to the presser 18 by a set screw 17^a and by being 70 slidably held in the dove-tail grooves 18^x, or by any other desired and convenient means. The screw 17^a passes through a flange 17^b.

Any suitable receiver may be provided for the addressed articles, after they have passed from under the 75 operation of the machine, and guide boards 33 may be also provided for convenience in feeding the articles to be pasted. The endless strip of addresses 100 passes from the reel over the drum 6^a and under the rod 8^b and from thence over the roller 10 between the rollers 80 11^a and 15, the rollers serving as feed rollers to draw the strip from the reel in the manner to be presently explained.

So far as described, the manner in which my invention operates can be best explained as follows:—After 85 the mailing list or strip has been placed in position, the papers are fed to the machine as indicated in Fig. 1, and the operator as each paper is in alinement with the presser 18 and the strip 100, presses down on the foot lever, which causes the arm 22 to be drawn downwardly in the direction indicated by the arrow in Fig. 3, which causes the knives 16—17 to cut the paper between the address portions thereof and simultaneously press the cut-off portion onto the paper being labeled. This causes the label to adhere to the 90 paper which can then be fed out of alinement with the strip and a new paper exposed.

It should be understood that as the strip 100 passes over the roller 10, the paste within the paste-pan 6 will be applied to the strip by the roller. As the operator releases the lever 29, the spring 28 will return the arm 26, adjacent the table and raise the arm 22 on its pivot, thus elevating the presser 18 to its starting position. It should be mentioned that a coil spring 118^a has one end connected to a pin 18^y on the presser 105 18 and to an adjustable arm 18^x mounted on the arm 22 so that the presser 18 will always normally tend to become elevated, as shown in Fig. 1 of the drawings. It should also be stated that as soon as the presser 18 is moved downward, when the foot lever is operated, 110 the heel 18^a thereof will engage the spring 30 and be forced to exert a shearing action in coöperation with the knife 16, on the address strip. As the foot lever is released, and the arm 22 elevated, the pawl 24 will operate upon the ratchet 20 to turn the gear 19 and pinion 11^b and thus cause the strip 100 to expose a 115 new addressed portion.

Instead of using foot power to operate the machine, I may operate the machine by connecting the rod 24 to a crank 35^a on a shaft 35 which may be geared with 120 the power shaft 36 through gears 35^b and 36^b. If desired, any suitable mechanical power may be applied to the shaft 36 to impart motion thereto, such power mechanism not being shown in the drawings, as the specific construction thereof *per se*, forms no part of 125 my present invention.

By adjusting the pawl 24 with its pin 24^a in the different apertures 23^b, the length of stroke of pawl 24 will be varied, and hence the length of the strip 100 which is fed out to the cutter will be varied propor- 130

tionately. This allows for addresses of different heights since by making the adjustment thus the strip will be adjusted proportionately.

From the foregoing description taken in connection with the accompanying drawings, it is thought the complete construction, operation and numerous advantages of my invention will be readily understood by those skilled in the art to which the invention appertains and I desire to say that slight changes in the 10 detail construction, combination and arrangement of parts can be made without departing from the spirit of the invention or the scope of the appended claims, and while I have shown and described my invention as particularly adapted for addressing periodicals, 15 yet the same may be used for addressing any article whatsoever as the machine can be readily adapted for articles of different forms by simply making the feed board higher or lower with respect to the cutting mechanism to such a degree as is necessary to permit 20 the article to pass under the cutting and pressing mechanism.

What I claim is:—

1. A bed plate, a bobbin supported thereon, a strip mounted on said bobbin, a paste-pan, guide members 25 pivotally mounted in bearings on said paste-pan between which said strip passes, a paste applying roller engaging the strip, combined with means for feeding the strip over the paste roller, and means for cutting the strip and applying the cut section of the strip to the article 30 to be labeled.

2. A bed plate, a bobbin supported thereon, a strip mounted on said bobbin, a paste-pan, guide members pivotally mounted in bearings on said paste-pan between 35 which said strip passes, a paste applying roller engaging the strip, combined with means for feeding the strip over the paste roller, means for cutting the strip and applying the cut section of the strip to the article to be labeled, together with a receiving board co-operatively supported beneath the cutting mechanism, substantially as shown 40 and described.

3. A strip carrying reel, means for applying paste to the strip, means for cutting the strip and pressing it against the article to be labeled, means for feeding the strip to the cutting and pressing means combined with 45 adjustable guides for the strip, together with a receiving board having a hinged wing, substantially as shown and described.

4. A strip carrying reel, means for applying paste to the strip, means for cutting the strip and pressing it 50 against the article to be labeled, means for feeding the strip to the cutting and pressing means combined with adjustable guides for the strip, together with a receiving board having a hinged wing, and a guide for the article being labeled.

5. In a machine of the class described, a bed plate, a bobbin mounted thereon to receive the address strip, a paste-pan mounted on the bed plate and having a drum portion adjacent the bobbin and a depressed portion merging with the drum portion, a pivotally supported bar held 60 within the paste-pan adjacent the depressed portion, under which bar the address strip is adapted to pass, a pasting roller mounted in bearings in the paste-pan, over which roller the address strip is adapted to pass, a feeding mechanism and a cutting mechanism, means for operating the feeding mechanism and the cutting mechanism, substantially as shown and described.

6. In an apparatus of the class described, a paste-pan having a drum shaped end, a pasting roller mounted in bearings in said paste-pan combined with a pivoted baffle 70 adjacent the drum shaped end, substantially as shown and described.

7. In an apparatus of the class described, a plurality of sets of relatively fixedly held feed rollers combined with a pivotally mounted roller carrying frame, feed rollers carried by the roller carrying frame, one for each pair of

relatively fixedly held feed rollers, a separate means for normally tending to hold said pivotally mounted frame with its rollers adjacent the relatively fixed feed rollers, together with a finger engageable and operated mechanism for moving the pivotally mounted frame on its fulcrum and swing the rollers in the arc of a circle out of proximity with the relatively fixed rollers, substantially as shown and described.

8. In a machine of the class described, a fixedly held knife, combined with a pivotally mounted arm, a movable knife pivotally mounted on said movable arm, means for swinging said movable arm on its pivot to bring its knife in co-operation with the fixedly held knife to cut the strip and press it against the article to which it is to be affixed, substantially as shown and described.

9. In a machine of the class described, a fixedly held knife, combined with a movable arm, and a knife pivotally connected with said movable arm, means for moving said movable arm with its knife into co-operation with the fixedly held knife to cut the strip and press it against the article to which it is to be affixed, together with means for engaging the pivotally connected knife as the movable arm is moved to cause the pivotally connected knife to effect a shearing action with the fixedly held knife, substantially as shown and described.

10. In an apparatus of the class described, a bed plate, an address strip carrying bobbin mounted thereon, a paste-pan mounted on said bed plate, said paste-pan having a drum portion adjacent the bobbin, a cross rod carried by the paste-pan adjacent the drum under which the address strip passes, a pasting roller carried by the paste-pan over which the addressing strip passes, guide arms carried by the paste-pan for co-operating with the strip, a feed mechanism for drawing the strip through the paste-pan, combined with a cutting mechanism, said cutting mechanism comprising a fixed knife, and a movable knife, and means for directing the movable knife into operative relation with the fixed knife to cut the strip, substantially as shown and described.

11. In an apparatus of the class described, a bed plate, an address strip carrying bobbin mounted thereon, a paste-pan mounted on said bed plate, said paste-pan having a drum portion adjacent the bobbin, a cross rod carried by the paste-pan adjacent the drum under which the address strip passes, a pasting roller carried by the paste-pan over which the address strip passes, guide arms carried by the paste-pan for co-operating with the strip, a feed mechanism for drawing the strip through the paste-pan combined with a cutting mechanism, said cutting mechanism comprising a fixed knife, and a movable knife,

means for directing the movable knife into operative relation with the fixed knife to cut the strip, said last named means comprising an arm pivotally mounted in bearings in the bed plate, a presser pivotally carried by said arm to which said movable knife is secured, means connecting the presser and the movable arm together to normally elevate the presser with relation to the arm, means for normally holding the arm elevated, and means for lowering the arm to bring the movable cutter into co-operative relation with the fixed cutter to cut the strip, substantially as shown and described.

12. In an apparatus of the class described, a bed plate, an address strip carrying bobbin mounted thereon, a paste-pan mounted on said bed plate, said paste-pan having a drum portion adjacent the bobbin, a cross rod carried by the paste-pan adjacent the drum under which the address strip passes, a pasting roller carried by the paste-pan over which the addressing strip passes, guide arms carried by the paste-pan for co-operating with the strip, a feed mechanism for drawing the strip through the paste-pan combined with a cutting mechanism, said cutting mechanism comprising a fixed knife, and a movable knife,

means for directing the movable knife into operative relation with the fixed knife to cut the strip, said last named means comprising an arm pivotally mounted in bearings in the bed plate, a presser pivotally carried by said arm to which said movable knife is secured, means connecting the presser and the movable arm together to normally elevate the presser with relation to the arm, means for normally holding the arm elevated, means for lowering the arm to bring the movable cutter into co-operative relation with the fixed cutter to cut the strip, substantially as shown and described.

the arm to bring the movable cutter into coöperative relation with the fixed cutter to cut the strip, together with means for engaging the presser as the movable arm guides it and the movable cutter into operative relation with the fixed cutter to effect a shearing action of the cutters to cut the strip, substantially as shown and described.

13. A machine of the class described, comprising the following elements in combination, a bed plate, an endless strip carrying bobbin mounted thereon, a paste-pan mounted in alinement with said bobbin, pasting means carried within the paste-pan, a fixed knife carried by the bed plate, a presser, a knife carried by said presser for coöperating with the fixed knife, means for normally holding the entire presser and its knife elevated, means interposed between the paste-pan and the fixed knife for feeding the address strip over the pasting means and to the knife and presser mechanism, means for lowering the presser and its knife into operative relation with the fixed knife to cut the strip and press the cut portion against the article to be labeled substantially as shown and described.

14. A machine of the class described, comprising the following elements in combination, a bed plate, an endless strip carrying bobbin mounted thereon, a paste pan mounted in alinement with said bobbin, pasting means carried by the paste-pan, a fixed knife carried by the bed plate, a presser, a knife carried by said presser for coöperating with the fixed knife, means for normally holding said presser and its knife elevated, means interposed between the paste-pan and the fixed knife for feeding the address strip over the pasting means and to the knife and presser mechanism, means for lowering the presser and its knife into operative relation with the fixed knife to cut the strip and press the cut portion against the article to be labeled, and means coöperating with the presser for effecting a shearing action between said knives, substantially as shown and described.

15. A machine of the class described, comprising the following elements in combination, a bed plate, an endless strip carrying bobbin mounted thereon, a paste-pan mounted in alinement with said bobbin, pasting means carried by the paste-pan, a fixed knife carried by the bed plate, a presser, a knife carried by said presser for coöperating with the fixed knife, means to which said presser is pivotally secured for normally holding said presser and its knife elevated, means interposed between the paste-pan and the fixed knife for feeding the address strip over the pasting rollers and to the knife and presser mechanisms, means for lowering the presser and its knife into operative relation with the fixed knife to cut the strip and press the cut portion against the article to be labeled, and means engaging the presser while being lowered to move the same on its pivot to effect a shearing action between the knives, substantially as shown and described.

16. A machine of the class described, comprising the following elements in combination, a bed plate, an endless strip carrying bobbin mounted thereon, a paste-pan mounted in alinement with said bobbin, pasting means carried by the paste-pan, a fixed knife carried by the bed plate, a presser, a knife carried by said presser for coöperating with the fixed knife, means for normally holding said presser and its knife elevated, means interposed between the paste-pan and the fixed knife for feeding the address strip over the pasting means and to the knife and presser mechanism, means for lowering the presser and its knife into operative relation with the fixed knife to cut the strip and press the cut portion against the article to be labeled, means coöperating with the presser for effecting a shearing action between said knives, an article guide-board carried by the bed plate, and a feed board adjustably mounted on a projecting portion of the bed plate.

17. In a machine of the class described, a bed plate having an elongated portion and a laterally projecting portion, a pair of uprights mounted at one end of said elongated portion, a strip carrying bobbin mounted at the other end of said elongated portion, a paste-pan interposed between the uprights and the bobbin and in alinement therewith, said paste-pan having a drum shaped end adjacent the bobbin, a bar carried by the paste-pan adjacent the drum under which the address strip passes, a paste applying roller carried by the paste-pan over which the address strip passes,

a pair of guides adjustably carried by the paste-pan for engaging each side of the address strip as it passes there across, a relatively fixed knife adjustably mounted on the bed plate between the uprights, a rotatable shaft mounted in said uprights, feed rollers carried by said rotatable shaft, said rotatable shaft projecting through one of said uprights, a pinion carried by the projecting portion of said shaft, a stub shaft carried by one of said uprights, a gear mounted on said stub shaft for engaging said pinion, a ratchet carried by said gear and stub shaft, a roller carrying frame pivotally mounted between said uprights, rollers carried by said frame for coöperating with the first mentioned feed rollers, means for normally holding the pivotally mounted frame with its rollers adjacent the first mentioned feed rollers, said address strip passing between said feed rollers, bearings mounted on said projecting portion of the bed plate, an arm pivotally mounted in said bearings, a presser pivotally mounted on the end of said arm, a knife carried by said presser for coöperating with the guides on the bed plate, a spring connecting the presser and the pivotally mounted arm for normally holding the presser elevated with relation to the arm, a post carried by the pivot portion of said arm, a pawl carried by said post and having an end for engaging said ratchet, means for normally holding said arm elevated, and means for drawing said arm down at times, substantially as shown and described.

18. In a machine of the class described, a bed plate having an elongated portion and a laterally projecting portion, a pair of uprights mounted at one end of said elongated portion, a strip carrying bobbin mounted at the other end of said elongated portion, a paste-pan interposed between the uprights and the bobbin and in alinement therewith, said paste-pan having a drum shaped end adjacent the bobbin, a bar carried by the paste-pan adjacent the drum under which the address strip passes, a paste applying roller carried by the paste-pan over which the address strip passes, a pair of guides adjustably carried by the paste-pan for engaging each side of the strip as it passes there across, a relatively fixed knife adjustably mounted on the bed plate between the uprights, a rotatable shaft mounted in bearings in said uprights, feed rollers carried by said rotatable shaft, said rotatable shaft projecting through one of said uprights, a pinion carried by the projecting portion of said shaft, a stub shaft carried by one of said uprights, a gear mounted on said stub shaft for engaging said pinion, a ratchet carried by said gear and stub shaft, a roller carrying frame pivotally mounted between said uprights, rollers carried by said frame for coöperating with the first mentioned feed rollers, means for normally holding the pivotally mounted frame with its rollers adjacent the first mentioned feed rollers, said address strip passing between said feed rollers, bearings mounted on said projecting portion of the bed plate, an arm pivotally mounted in said bearings, a presser pivotally mounted on the end of said arm, a knife carried by said presser for coöperating with the knife on the bed plate, a spring connecting the presser and the pivotally mounted arm for normally holding the presser elevated, with relation to the arm, a post carried by the pivot portion of said arm, a pawl carried by said post and having an end engaging said ratchet, means for normally holding said arm elevated, means for drawing said arm down at times, and means for engaging the presser as the arm is drawn down to cause the cutter knives to effect a shearing action on the address strip and a feed-board held under the cutting mechanism, substantially as shown and described.

19. In an apparatus of the class described, an endless strip carrying bobbin, paste applying means, a pair of pivotally mounted strip side engaging guides mounted adjacent the paste applying means, means for feeding the endless strip over the paste applying means between the guides and to the articles to be labeled, combined with means for cutting a section off of the strip and applying it to the article to be labeled.

JOHN C. THOMSON.
